UNITED STATES PATENT OFFICE.

HARRY M. CLARK, OF NEW YORK, N. Y., ASSIGNOR OF ONE-HALF TO
CHARLES R. WEBSTER, OF SAME PLACE.

DESIGN FOR A NAPKIN-HOLDER.

SPECIFICATION forming part of Design No. 32,650, dated May 15, 1900.

Application filed April 17, 1900. Serial No. 13,273. Term of patent 14 years.

To all whom it may concern:

Be it known that I, HARRY M. CLARK, a citizen of the United States, residing at New York city, in the county of New York and State 5 of New York, have invented a certain new and useful Design for a Napkin-Holder; and I do declare the following to be a full, clear, and exact description of the invention, such as will enable others skilled in the art to which it appertains to make and use the same.

My invention relates to a new and useful design for a napkin-holder, and the figure in the drawing is a perspective view of a napkin-holder embodying my design and which 15 is the subject of my invention.

The leading feature of my design consists of the oblong loop *a*, the straight diverging sides

b b, and the inwardly-curved arms *c c*, crossing each other and interlocking at their meeting-point *d* and having their free diverging 20 ends terminating in the closed eyes *e e*.

Having thus fully described my invention, what I claim as new and useful, and desire to secure by Letters Patent of the United States, is—

The design for a napkin-holder, substantially as herein shown and described.

In testimony whereof I have hereunto set my hand in presence of two subscribing witnesses.

HARRY M. CLARK.

Witnesses:

C. O. FRENCH,
GEO. SHELDICK.
